Des. 229,110
Patented Nov. 6, 1973

229,110

WRITING INSTRUMENT

Francisco Barcelloni Corte, Corrientes 2021,
Buenos Aires, Argentina

Filed Sept. 22, 1971, Ser. No. 182,928

Claims priority, application Brazil Mar. 12, 1971

Term of patent 14 years

Int. Cl. D19—06
U.S. Cl. D74—17 B

FIG. 1 is an elevational view of the front half of a writing instrument embodying my ornamental design in which the cap is disposed over the writing nib;

FIG. 2 is a similar view of the opposite half of the writing instrument in which the cap is removed to expose the writing nib; and

FIG. 3 is a plan view of the writing instrument looking at the writing nib end, exposed as in FIG. 2.

I claim:

The ornamental design for a writing instrument, substantially as shown.
